SAW MITER GUIDE

Aldor S. E. Reuterfors, Rockford, Ill., assignor to Estwing Manufacturing Company, Inc., Rockford, Ill., a corporation of Illinois

Filed Aug. 29, 1967, Ser. No. 8,418

Term of patent 14 years

(Cl. D52—6)

FIG. 2 is a side view showing one side thereof;

FIG. 3 is an end view showing one end thereof;
FIG. 4 is a side view showing the side opposite the side shown in FIG. 2; and

FIG. 5 is an end view showing the end opposite the end shown in FIG. 3.

I claim:

The ornamental design for a saw miter guide, as shown.
